UNITED STATES PATENT OFFICE.

JOHN W. EVANS, OF CLEVELAND, OHIO.

EXTRACTING OIL.

SPECIFICATION forming part of Letters Patent No. 443,907, dated December 30, 1890.

Application filed May 5, 1890. Serial No. 350,603. (No specimens.)

To all whom it may concern:

Be it known that I, JOHN W. EVANS, of Cleveland, in the county of Cuyahoga and State of Ohio, have invented certain new and useful Improvements in what is known as the Naphtha Process of Extracting Oil; and I do hereby declare the following to be a full, clear, and exact description of the invention, such as will enable others skilled in the art to 10 which it pertains to make and use the same.

My invention relates to improvements in what is known as the "naphtha process" of extracting oil. In extracting oil by the naphtha process—for instance, from linseed—the 15 seed is ground and placed in a percolator, and the latter is then charged with hot naphtha as a solvent. After a time the united oil and naphtha is drawn off at the bottom of the percolator, or at least so much of the mixture 20 is drawn off as will separate itself from the meal by gravity. There will still remain in the meal more or less naphtha and a small percentage of oil, the former being distributed throughout the mass of meal, while the remaining oil will be distributed in the lower 25 portion of the meal near the bottom of the percolator. The discharge-pipe at the bottom of the percolator is then closed and the eduction vapor-pipes are opened and live 30 steam is introduced into the meal in the percolator to evaporate the remaining naphtha, the naphtha vapor being conducted to a condenser, from whence the liquid naphtha is returned to its tank to be again used for extracting the oil from the next batch of meal. 35 A suitable percolator for carrying out this process is shown and described in United States Letters Patent No. 381,062, granted to me April 10, 1888, and to which reference is hereby made, and for convenience for reference in this specification the percolator is outlined in the accompanying drawing, the same being an elevation in section through the center of the percolator.

45 A represents the percolator, and B a pipe connecting with the bottom of the percolator for drawing off the united oil and naphtha. C are eduction vapor-pipes. D is a steam-pipe encircling the percolator 50 and from which extend smaller branch pipes d, connecting, respectively, with the different hollow perforated arms arranged inside the percolator in series at different elevations at E, E', and E². These arms, as shown, extend radially toward the center of the percolator, 55 and for convenience in removing the material these arms are mounted on hollow trun- nions, so that the different arms may be folded down alongside of the walls of the percolator. It is believed that this brief description of 60 the percolator will be sufficient for a full understanding of my improved process.

Before filling the percolators the different hollow arms are extended and held in a horizontal position and the valves of pipes B and 65 C are closed. After the meal and hot naphtha with which the percolator is charged has remained for a suitable length of time valve b of pipe B is opened to draw off the mixed oil and naphtha, and after this has been ac- 70 complished, so far as gravity will effect such separation of the oil and solvent from the meal, valve b is closed. Next the valves of pipes C are opened and live steam from pipe D is admitted through pipe d to the hollow 75 arm to evaporize the naphtha remaining in the meal.

Heretofore steam was first admitted to the upper series of arms E, by means of which the naphtha from the upper portion of the 80 meal was readily evaporated, the naphtha vapor passing off through pipe C to a condenser. (Not shown.) After a time the steam was shut off from arms E and was introduced into arms E'. The naphtha from the 85 central portion of the meal is evaporated and expelled more slowly, owing to the depth of material above that has been rendered more compact by the previous steaming. Eventually the steam was shut off from arms E' 90 and admitted into the lower arms E² to evaporate the naphtha from the meal at or near the bottom of the percolator. This last stage was much more difficult and tedious, owing to the great depth of material above and 95 owing to the fact that the upper portion of the meal had been rendered compact and clammy by previous steaming. Hence it was necessary to employ a higher pressure of steam for evaporizing the naphtha and ex- 100 pelling the vapors thereof from the lower portion of the meal. Another objectionable feature was that the residue of oil in the lower portion of meal was carried up with the naph-

tha vapor and distributed beyond recovery throughout the whole mass of the meal.

To more clearly define my improved method hereinafter mentioned, I will remark that the 5 linseed-meal had from the naphtha process is considered a valuable food for animals, more especially as the albumen of the seed is left entirely in the meal, and hence the oil is pure, as the albumen if left in the oil is an 10 impurity and has to be subsequently removed by some process of refining to produce a good quality of oil; also, any oil left in the meal not only deteriorates the latter, but the purchaser in buying meal by the pound does not 15 care to pay for what is worse than useless in the meal—to wit, the remaining oil—and the manufacturer does not wish to sell oil at the price per pound of meal. It is therefore important from both standpoints that as far as 20 possible the highest per cent. of oil be extracted from the meal.

In carrying out my improved method I provide an eduction vapor-pipe leading from the bottom of the percolator, such pipe being 25 shown at C'. This pipe is more conveniently attached to pipe C as a branch of the latter, pipe C' being provided with a valve c'. This is the only addition that I make, and otherwise the percolator is left in the same condition 30 as heretofore. Of course another condenser is provided for condensing the naphtha vapors escaping through pipe C'. Now in "steaming out" the naphtha steam is admitted to the central arm E' and immediately 35 after to arms E and E². The vapor from different portions of the percolator may therefore take the shortest and easiest route, whichever it may be, up or down, and the lower portion of the meal in the percolator is 40 freed from naphtha as expeditiously as the upper portion, the steaming out requiring less than half the time formerly required; also, the residue of oil that, as aforesaid, is found in the lower portion of the meal is carried 45 downward by the escaping naphtha vapor, and about all of it is thus saved, the oil pass-

ing off in the naphtha vapor through pipe C' and uniting with the naphtha condensed in the lower condenser, and no effort at the time is made to recover this oil, from the fact that 50 the naphtha in this condenser is returned to its tank and is used over again in the next operation, and hence this oil is not lost.

To recapitulate: With my improved method, whereby the naphtha vapor may escape simultaneously from the top and bottom of the percolator, first, a large percentage of oil is obtained, the absence of which in the meal renders the latter more valuable, and also is avoided the excessive cooking of the meal at 60 the upper portion of the percolator and the consequent wet and clammy condition of this when removed from the percolator, and the steaming-out process is accomplished in less than half the time formerly required. 65

In conclusion I will state the facts that the percolators that I am using have a capacity of eight hundred and twenty-five bushels of meal, and with my improved method herein-before described I am enabled to save two 70 barrels of oil for each charge of a percolator more than I could save when operating the percolators without the lower vapor-pipe—that is to say, steaming out the naphtha with the escape of the naphtha vapors only at the 75 top of the percolator.

What I claim is—

In what is known as the naphtha process of extracting oil, the method herein described, consisting, essentially, of introducing steam 80 into different portions of the percolator and simultaneously exhausting the naphtha vapor from the top and bottom of the percolator, substantially as set forth.

In testimony whereof I sign this specification, in the presence of two witnesses, this 24th day of April, 1890.

JOHN W. EVANS.
